RAILWAY CAR DRAFT SILL

Filed April 5, 1929

UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

RAILWAY CAR DRAFT SILL

Original application filed April 18, 1928, Serial No. 270,950. Divided and this application filed April 5, 1929. Serial No. 352,818.

My invention relates to railway rolling stock and consists in a novel draft sill, coupler carrier and associated structure, and the present application is a division of my application, Serial No. 270,950, filed April 18, 1928, and illustrating and describing a complete hopper ore car underframe in which the present structure is advantageously used, although also adapted for general use in cars.

10 One of the objects of my invention is to provide an improved coupler-carrying element adapted to withstand deflection tendencies caused by the buffing and pulling forces incident to the use of heavier cars and the 15 greater loads carried thereby.

Another object of my invention is to provide draft sills and associated structure having strength to withstand the abuse that a heavy steel hopper car loaded to capacity with 20 heavy material is bound to bring upon draft gear and its mounting.

In the accompanying drawings which illustrate a selected embodiment of my invention:

25 Figure 1 is a top view of the longitudinal half of one end of a hopper car underframe including my novel structure.

Figure 2 is a longitudinal vertical section taken on the center line of the underframe 30 shown in Figure 1.

Figures 3 and 5 are vertical sections taken on lines 3-3 and 5-5 respectively of Figure 1.

Figure 4 is an end view of the striking plate, draft sills and coupler carrier.

Figure 6 is a horizontal section taken on line 6-6 of Figure 2.

The draft framing in the preferred form of my invention is integral with the remainder of the underframe. Each of said draft sills 7 is box-shaped in cross section with closed front ends and the sills are parallel with the longitudinal axis of the car, being spaced to receive the necessary draft rigging. The outside walls of the draft sills 7 curve outwardly so as to merge with the front wall of the corresponding bolster 9.

The inside walls of the draft sill merge with diagonal members D which assist the bolster in transmitting longitudinal forces

to the center sills C. This structure forms the subject matter of my above mentioned co-pending application.

The outer ends of draft sills 7 are integrally connected by an upper web 10, having a depending flange 10a forming the striking plate, and by a channel-shaped coupler carrier member 11 which has its web 12 disposed vertically and its flanges 13 and 14 disposed horizontally and extending inwardly from the end of the car and connecting the lower portions of the draft sills 7. Ribs 15 brace the flanges intermediate their ends. If preferred, the coupler carrier may be made of I-beam or box shape or other desired cross section.

The inside walls of the draft sills 7 are provided with draft lugs S and T. The outside walls of the draft sills are provided with elongated openings 16 to permit insertion and longitudinal movement of the draft gear. Side springs and the openings 17 in the inside walls of the sills permit insertion and longitudinal movement of the side spring shaft. The openings 18 permit insertion and longitudinal movement of the draft keys.

One draft sill 7 and the diagonally opposite draft sill 7 at the opposite end of the car are provided with laterally extending brackets 19, integral with the sills 7 and adapted to mount hand brake rigging (not shown). Each of these brackets extends outwardly from the draft sill and is reinforced with suitable integral upright ribs 20 connecting the bracket and the lower portion of the wall of the draft sill.

The bolster construction and the parts at the rear of the bolster do not form part of the subject matter claimed in this application but are illustrated to show the type of underframe for which my draft sill, coupler carrier and associated structure are designed. They illustrate a relatively heavy underframe construction adapted to carry relatively heavy loads. These parts, however, may be altogether different and the details of the structure claimed herein may be modified without departing from the spirit of my invention and I contemplate the exclusive use

of such variations as come within the scope of my claims.

I claim:

1. In a railway car draft framing, draft sills, and a channel-shaped coupled carrier element integral with said draft sills.
  2. In a railway car draft framing, draft sills, and a channel-shaped coupler carrier element integral with said draft sills and connecting their outer ends.
  3. In a railway car draft framing, draft sills, a channel-shaped coupler-carrying element integral with said draft sills and having a vertically disposed web and inwardly extending flanges, and a web connecting the tops of said sills and having a depending flange substantially aligned with the web of said element.
  4. In a railway car draft framing, draft sills, a channel-shaped coupler-carrying element connecting the lower outer ends of said sills and integral therewith, and a hand brake bracket projecting outwardly from and integral with one of said sills near the end of the same.
  5. In a railway car draft framing, box-shaped draft sills each having outside and inside walls, there being elongated openings in the outer walls of said sills for insertion of draft keys, and draft lugs integral with the inner walls of said sills.
  6. In a railway draft framing, draft sills, a channel-shaped coupler-carrying element with a vertically disposed web and horizontally disposed flanges, said element being integral with said sills and connecting the bottom of their outer ends.
  7. A railway car draft sill having inner and outer walls, said outer wall being provided with a horizontally extending bracket for mounting a hand brake, there being an upright reinforcing rib connecting said bracket and the lower portion of said wall.
  8. In combination, draft sills, a channel-shaped coupler-carrying element with a vertically disposed web and horizontally disposed flanges, said element being integral with said sills and connecting the bottom of their outer ends, a web integral with said draft sills connecting the top of said draft sills and having a depending flange forming a striking plate, draft lugs integral with said draft sills, said sills being provided with elongated openings between said lugs to permit insertion and movement of draft gear side spring shafts.
  9. In a railway car draft framing, draft sills each having an inner and an outer wall, and a channel-shaped coupler carrier extending between said inner walls and integral therewith.
  10. In a railway car draft framing; draft sills; and a coupler carrier element integral with said sills and comprising a vertical web, an upper flange extending inwardly of the car, a wider lower flange extending similarly, and ribs between said flanges intermediate said sills.
  11. In a railway car draft framing, box-shaped draft sills with closed ends, and a striking plate integral with said sills and comprising a horizontal web flush with the tops of said sills and a depending flange on said web flush with the ends of said sills.
  12. In a car underframe, spaced draft sills, and a coupler carrier element between said sills, said element being of channel-shaped cross section with its web disposed vertically.
  13. In a car underframe, spaced draft sills, and a coupler carrier element between said sills, said element comprising a vertically disposed web with horizontal flanges extending inwardly of the underframe.
  14. In a car underframe, an integral casting comprising spaced draft sills of box-shaped cross section connected near their forward end by a channel-shaped coupler carrier having its web upright.
  15. In a car underframe, spaced draft sills, each of said sills having spaced vertical walls, the inner walls comprising a draft gear housing, and each wall having an elongated opening for application of a draft gear side spring shaft and movement of the same longitudinally of the sill and each outer wall having a larger opening for receiving a draft spring and accommodating movement of the same longitudinally of the sill.
  16. In a car underframe casting, a draft sill spaced from the longitudinal center line of said casting and having spaced vertical walls, the inner side of the inner wall having a draft gear stop lug and the outer wall having an elongated opening for application of a draft gear side spring and for movement of the same longitudinally of the sill.
- In testimony whereof I hereunto affix my signature this 1st day of April, 1929.
